UNITED STATES PATENT OFFICE.

ELMER ENGSTROM, OF SOUTH WINDHAM, CONNECTICUT.

APPARATUS FOR FEEDING FOLDED PAPER TUBES OR THE LIKE.

Application filed April 27, 1926. Serial No. 105,023.

The apparatus of the present invention, while primarily designed for feeding flat paper tubes into a bottoming, or other bag finishing or printing machine, is well suited 5 for a wide range of utility in the arts, and is adapted for feeding practically any type of paper sheets or similar material.

An object of the invention is to provide an apparatus of this character which is adapted 10 to remove one sheet at a time from the bottom of a stack of sheets, and to withdraw the sheet from the bottom of the stack in such a manner that there will be no sliding contact between the sheet which is withdrawn, and the sheet immediately there- 15 above.

In a preferred embodiment of the invention, a series of stacked sheets are disposed in a hopper. Approximately one half of a 20 rotating turntable constitutes the bottom of the hopper. The turntable is radially slotted at any suitable number of points for the passage of a sheet from the upper to the lower side of the turntable. Separating 25 tongues are provided at the slots in the turntable, and suction devices automatically draw the corner of the lowermost sheet downwardly and pass it under one of the separating tongues. Continued revolution 30 of the turntable serves to separate the lowermost sheet from the stack without causing any relative sliding movement between said lowermost sheet and the stack. After the turntable has been rotated through a predetermined distance, the lowermost sheet will 35 drop under the turntable either on to a suitable conveyor or on to some other receptacle where some operation on the sheet is to be performed.

40 Preferably as the sheet passes under the turntable it is received between a pair of feeding rollers which are turning at the surface speed of the turntable so that the sheet will be positively separated from the pack without sliding relative thereto.

45 Preferably also the turntable is equipped with antifriction rollers for supporting the main stack of material to be fed and relieving friction between the turntable and the bottom of the stack.

50 Other objects of the invention are to provide an apparatus which will be rugged and durable in use, which will combine simplicity of construction with automaticity of

operation, and which may be manufactured 55 with comparative economy.

With the above noted and other objects in view, the invention consists in certain novel features of construction and combinations and arrangements of parts, as will be more 60 fully hereinafter set forth and pointed out, in the claims. The invention may be more 65 fully understood from the following description in connection with the accompanying drawings, wherein—

Fig. 1 is a top plan view of a paper feeding apparatus embodying the present invention.

Fig. 2 is a vertical sectional view there- 70

Fig. 3 is a transverse sectional detail 75 through the suction roller and associated parts.

Fig. 4 is a similar view, but showing the turntable moved to a slightly advanced position.

In the drawings I have not attempted to indicate in full the frame work of the machine, but have only shown the particular 80 portions of the frame work which mount the turntable, the hopper or frame, and an end roller of the endless conveyor on to which the sheets removed from the hopper are deposited.

As best seen in Fig. 1 the frame of the 85 machine includes a vertical frame bar 10 formed with a bearing 11 which mounts the drive shaft 12 of the machine. Drive shaft 12 carries a bevelled driving pinion 13 co- 90 acting with a crown gear 14 to drive a vertical spindle 15 to which the crown gear is rigidly connected as by a set screw 16. A bearing sleeve 17 for the spindle 15 forms part of the frame work of the ma- 95 chine, and may be carried on a vertical standard 18 connected to frame member 10 by a cross piece 19. A turntable 20 is mounted on the spindle 15, and the upper reduced end 21 of the spindle is borne in a block 22 rigidly secured to the upper end of the 100 frame member 18 at a point above the spindle.

105 Preferably the block 22 is directly bolted to a vertical gauge plate 23 which constitutes the stationary side wall of a frame which receives the stacked sheets of material 24 to be fed. The ends of the gauge plate are in turn directly secured to the frame

member 18 in any appropriate manner (not shown).

The gauge plate is disposed approximately diametrically of the turntable 20, but 5 slightly to one side of the center thereof, so that nearly half of the turntable extends under the gauge plate and constitutes the movable bottom for the sheet retaining hopper or frame.

10 It will be noted that the frame member 10 at its upper end mounts a longitudinal slotted frame bar 26. Vertical corner standards 27 and 28 are formed with horizontal extensions 29 at their lower ends overlying the rail 26 and adjustably secured to this rail by screws 30 working through the slot 31 in the rail and wing nuts 22 coacting with the screws. The extensions 29 are also longitudinally slotted at 33, so that by adjusting 15 the screws 30 and the wing nuts 32, the angular corner pieces 27 and 28 may be moved toward each other, or may be shifted inwardly toward the stationary gauge plate 23.

20 In Fig. 1 I have indicated in dotted lines 25 at 34 the smallest sized sheet which may be conveniently received by the gauge plate 23 and the corner pieces 28, and have shown in full lines the corner pieces adjusted to accommodate a maximum sized sheet of material. It will be noted that this sheet has one edge abutting the gauge plate 23 and the corners received in the angular corner pieces 27, 28. The largest sized sheet which 30 can be accommodated is of a length approximately equal to the diameter of the turntable, and of a width slightly less than the radius of the turntable.

35 Supported at one end in the frame work of the machine, and at the other end in any 40 approved manner, is an endless conveyor 35. A roller 36 is journalled between the frame members 10 and 18 and constitutes one support for the endless conveyor. Means is associated with the turntable 20 for removing the lowermost sheet of the stack 25, passing it through the turntable, and delivering it on to the endless belt 35. It is to be understood however, that the particular disposition which is made of the sheet after 45 its removal from the stack is immaterial to the present invention, and that I have simply illustrated the endless conveyor as one sheet handling apparatus which may be used for carrying the sheets 25 to a distant point. In practice when the machine is used for feeding collapsed paper tubes, the belt 35 will carry the individual tubes to a bottoming, printing or other finishing machine.

50 The turntable may be arranged for feeding 60 any suitable number of sheets 25 in the course of a single revolution of the table. For purposes of illustration I have shown a mechanism by which four sheets are delivered from the stack to the conveyor upon each revolution of the turntable. It is to

be understood that the number of sheets which are fed will depend altogether upon the particular use to which the apparatus may be put, the rate of revolution of the turntable and other factors which must be determined in the case of each particular use to which the machine is put.

The turntable is provided with four 55 equally spaced radial slots 40. The turntable is rotated in a counter clockwise direction, and the material near the outer end of the following edge of each slot provides a separating tongue 41 sharply bevelled at 42 on its under face as best seen in Figs. 3 and 4. Mounted immediately adjacent each slot 40 beneath the surface of the turntable is a suction roller 44 of frustro conical shape, the tapered sides of the roller being coincident with two radii of the turntable. The rollers at their inner ends are borne in bearings 43 and at their outer ends rotate upon the inner 60 ends of hollow cylindrical blocks 44 secured in recesses in the outer edges of the turntable by set screws 46. The hollow cylindrical blocks 45 are integrally closed at their inner ends and closed by plugs 47 at their outer ends. The blocks are formed with lateral air ports 48 adapted to register with similar radial ports 49 in the rollers 44 when the rollers have been rotated to proper position.

The hollow interiors of the cylinders 45 are adapted to be connected through branch pipes 50 to a main air pipe 51 stationarily 65 axially mounted within the hollow spindle 15 of the turntable. Any suitable means 100 (not shown) is used to create a suction in the air pipe 51, consequently in the cylinder 45 of the rollers 44 whose pipe 50 is aligned with the port 51^a of the air pipe 51. When 105 this suction is produced in the cylinder 45, its associated roller will have been rotated to align the ports 48 and 49 and there will be a draft of air inwardly through these ports. Port 51^a is arranged to register with 110 a pipe 50 whose associated roller is under the edge of the stacked sheets, whereby to pneumatically draw down the corner of the lowermost sheet 25.

115 Means is provided for rotating the rollers 44 in their bearings at the same surface speed as the speed of the turntable 20, and the size of the rollers 44 is such that they will complete a revolution to every quarter 120 revolution of the turntable. The movement 125 of the rollers 44 is so timed that whenever one of the separating tongues 41 reaches the position shown in Fig. 3, the ports 48 and 49 will be aligned, and the pipe 45 of the roller will register with port 51^a, and 130 the corner of the lowermost sheet 25 of the stack will be pneumatically drawn down and passed under the edge of the separating tongue, this sheet being drawn between the roller 44 and a cooperating friction roller 130

55 mounted in the turntable at the edge of the slot 40. Continued movement of the turntable will cause the lowermost sheet 25 of the stack to be positively fed between the 5 rollers 44 and 55, so that by the time the turntable has moved through a predetermined distance, the sheet will be entirely separated from the stack on top of the turntable, and will drop on to the conveyor 35.

10 From this description of operation, the advantage of rotating the rollers 44 at the surface speed of the turntable will be obvious. It is this speed ratio which eliminates the drag of a sheet from the bottom of the 15 stack and the relative sliding movement between the lowermost sheet and the remaining sheets. Instead of a sliding or dragging action the turntable simply acts as a separator to positively separate the lowermost sheet from the remainder of the stack and drop it on to the conveyor.

The particular mechanism which is utilized for driving the rollers 44 at a predetermined speed ratio to the turntable 20 is subject to a wide variety of variations, but I have illustrated one mechanism in which a plurality of reducing gears are utilized, and which has been found suitable for the purpose.

20 The rollers 44 are coupled for turning movement to radial shafts 60, the inner ends of which are borne in suitable sockets 61 in the spindle 15. Near their inner ends shafts 60 carry bevelled pinions 62 driven through 25 a suitable gear reducing train from a gear 63 keyed to the upper end of the spindle 15 above the block 22. The particular gear train illustrated includes a pinion 64 meshing with the gear 63 and driving a gear 65 30 keyed to a countershaft 66 journalled in the block 22. To the lower end of the counter shaft 66 is fixed a gear 67 meshing with a gear 68 which encircles the reduced end of the spindle 15 below the block 22. Gear 68 35 is integral or rigid with a bevelled gear 69 meshing with all of the pinions 62. Thus, by following through the reducing gear train, it will be seen that the rollers 44 are turned in the same direction as the turntable, to wit: in a counter clockwise direction, and are driven at the same surface speed as the turntable.

40 Preferably some means is provided for relieving the friction between the turntable and the bottom of the stack of sheets 25. I have shown this means as including any suitable number of radially disposed anti-friction rollers 70 which support the main weight of the stack as the turntable passes thereunder.

45 While the operation of the device will be more or less apparent from the foregoing description, it may be briefly summarized as follows. Drive shaft 12 rotates the turntable spindle through the medium of the

50 pinion 13 and gear 14. The turntable is thus rotated at any predetermined speed in a counter clockwise direction. The rotating turntable serves as the bottom of the adjustable hopper or frame for the stacked sheets 25, friction rollers 70 serving to relieve friction between the bottom of the stack and the turntable. Rollers 44 are driven through the reducing gear train above described from the spindle 21, and are 55 so arranged, that when one of the separating tongues 42 of the turntable reaches the corner of the stacked sheets 25, ports 49 of the roller 44 will be open to the suction line 51, and the corner of the sheet will be 60 drawn down under the separating tongue. As this sheet passes under the tongue, it is gripped between rollers 55 and 49 and positively separated from the stack without being displaced laterally relative thereto. The 65 separated sheets drop on to the conveyor 35 and are carried to any suitable point.

Obviously various changes and alterations might be made in the general form and arrangement of parts described without departing from the invention. Hence I do not wish to limit myself to the details set forth, but shall consider myself at liberty to make such changes and alterations as fairly fall within the spirit and scope of the 95 appended claims.

I claim:

1. A paper sheet feeding mechanism including a rotating turntable, a frame arranged above the turntable and laterally supporting a stack of sheets which rest on the turntable, said turntable having a radial slot therein, a separating tongue at the following edge of the slot, and roller means operating at the surface speed of the turntable for drawing the corner of the lowermost sheet downwardly under the separating tongue.

2. A paper sheet feeding mechanism including a turntable, a frame arranged above the turntable and laterally supporting a stack of sheets which rest on the turntable, said turntable having a radial slot therein, a separating tongue at the following edge of the slot, and a suction roller for drawing the corner of the lowermost sheet downwardly under the separating tongue.

3. A paper sheet feeding mechanism including a turntable, a frame arranged above the turntable and laterally supporting a stack of sheets which rest on the turntable, said turntable having a radial slot therein, a separating tongue at the following edge of the slot, a suction roller for drawing the corner of the lowermost sheet downwardly under the separating tongue, and a suction line, the roller including air ports adapted to be placed in communication with the suction line at the time that the roller passes under the corner of the lowermost sheet.

4. A paper sheet feeding mechanism including a turntable, a frame arranged above the turntable and laterally supporting a stack of sheets which rest on the turntable, said turntable having a radial slot therein, a separating tongue at the following edge of the slot, a suction roller for drawing the corner of the lowermost sheet downwardly under the separating tongue, and a friction roller coacting with the suction roller to positively grip the corner of a sheet as it is fed under the supporting tongue.

5. A paper sheet feeding mechanism including a turntable, a frame arranged above the turntable and laterally supporting a stack of sheets which rest on the turntable, said turntable having a radial slot therein, a separating tongue at the following edge of the slot, a suction roller for drawing the corner of the lowermost sheet downwardly under the separating tongue, and a friction roller coacting with the suction roller to positively grip the corner of a sheet as it is fed under the supporting tongue, said suction roller and turntable being mechanically rotated at the same surface speeds, whereby the lowermost sheet of a stack may be separated from the body of the stack without being laterally displaced relative to the body.

6. A paper sheet feeding mechanism including a turntable, a frame arranged above the turntable and laterally supporting a stack of sheets which rest on the turntable, said turntable having a radial slot therein, a separating tongue at the following edge of the slot, a suction roller for drawing the corner of the lowermost sheet downwardly under the separating tongue, a spindle for

rotating the turntable, and means for rotating the suction roller at the same surface speed as the turntable.

7. A paper sheet feeding mechanism including a turntable, a frame arranged above the turntable and laterally supporting a stack of sheets which rest on the turntable, said turntable having a radial slot therein, a separating tongue at the following edge of the slot, a suction roller for drawing the corner of the lowermost sheet downwardly under the separating tongue, a spindle for rotating the turntable, and means for rotating the suction roller at the same surface speed as the turntable, said last mentioned means including a gear reducing train actuated from the turntable spindle.

8. A device of the class described in claim 2, wherein the turntable is mounted on a driving spindle, and an air suction line is housed within the spindle and placed in communication with ports in the suction roller as said roller passes under the edge of the stack.

9. A paper sheet feeding mechanism including a turntable, a frame arranged above the turntable and laterally supporting a stack of sheets which rest on the turntable, said turntable having a radial slot therein, a separating tongue at the following edge of the slot, means for drawing the corner of the lowermost sheet downwardly under the separating tongue, whereby said tongue separates the sheet from the remainder of the stack upon continued rotation of the turntable, and friction rollers mounted in the turntable and supporting the weight of the stack.

ELMER ENGSTROM.
